SWITCHING ARRANGEMENT FOR AUTOMATIC AND SEMIAUTOMATIC TELEPHONE
SYSTEMS

Application filed June 13, 1929, Serial No. 370,673, and in Great Britain June 13, 1928.

This invention relates to telephone systems and more particularly to such systems in which a call is extended by means of automatic switches.

5 It is an object of the invention to provide an improved system of this type in which considerable simplification of the apparatus is effected.

According to a feature of the invention in 10 a system in which at each numerical switching stage are employed single-motion conversation selectors controlled by control switches each common to a plurality of conversation selectors but individual to the 15 switching stage to which said conversation selectors belong, a common control switch is set under the control of a register controller to which revertive impulses are sent during the advance of said control switch to a selected position.

This and other features of the invention will be better understood from a consideration of the following description taken in conjunction with the accompanying drawings which illustrate one embodiment of the 25 invention.

Referring now to the accompanying drawings,

Fig. 1 shows a subscriber's line and starting 20 circuit and a first line finder

Fig. 2 shows a second line finder common starting circuit arrangement

Fig. 3 shows a second line finder circuit

Fig. 4 shows a first group finder circuit

35 Fig. 5 shows a second group finder circuit

Fig. 6 shows a final finder circuit

Fig. 7 shows a first group finder control circuit

40 Fig. 8 shows a second group finder control circuit

Fig. 9 shows a final finder control circuit

Fig. 10 shows a register circuit including a register finder switch

45 Fig. 11 shows a false call circuit at an operator's position,

Fig. 12 shows a layout diagram showing the relative positions of the circuits illustrated in Figs. 1-11 in a typical system.

50 A general description will first be given with reference to Fig. 12.

When the telephone is removed from the switch hook at substation S the calling line is extended over first and second line finders 1LF, 2LF to a first group finder 1GF having an idle associated control circuit 1CF. 55 Immediately thereafter the link circuit comprising the second line finder 2LF and group finder 1GF becomes attached to an idle register circuit RC over a register finder PR whereupon dialling tone is sent to the calling party.

The subscriber dials in the usual way. The first digit dialled advances the thousands register in the register circuit to the corresponding position. When the first digit 60 has been received a signal is sent forward from the register circuit to cause the first group finder switch 1GF associated with the line finder 2LF to become connected with its associated control circuit, the finder switch 65 1CF of which is set in rotation and hunts until it finds the first group finder switch 1GF. The control finder 1CF is then further advanced to a position corresponding to the first digit dialled in which position it marks 70 the wanted group of trunks outgoing from the bank of the switch 1GF. During the last mentioned movement revertive impulses are sent back from the control finder 1CF to count out the thousands register switch in 75 the register circuit RC. The first group finder 1GF is now caused to hunt for a free trunk extending to a second group finder 2GF the associated control circuit 2CF of which is idle in the group determined by the setting 80 of control finder 1CF.

It should be noted that the trunks from the arcs of the group finder switches need not be arranged in any definite order and further the groups need not contain the same 85 number of trunks. Whenever it is found necessary to increase the number of trunks in a particular group this can be done without disturbing the existing connections the additional trunks being connected to any 90 spare positions in the arcs.

The further extension of the connection depends upon the type of call which is being set up. In the case of a normal call when the second digit has been dialled a signal is 95 100

again sent forward from the register circuit RC to cause the second group finder 2GF which has been taken for use to become attached to its control circuit, the finder 2CF of which is set in rotation and hunts until it finds the engaged second group finder 2GF. The control finder 2CF is then further advanced to a position corresponding to the second digit dialled to mark a wanted group of trunks in the bank of the finder 2GF, during this movement revertive impulses being sent back to the register circuit RC to count out the hundreds register switch therein. The second group finder 2GF is now caused to hunt in the wanted group for a free trunk to an idle final finder FF, the associated control circuit FCF of which is also idle.

When the tens digit and at least one impulse of the units digit have been received by the register circuit RC the control circuit FCF is taken into use and its finder switch hunts until it picks up the final finder FF. The control finder switch then advances further to a position corresponding to the tens digit, during this movement revertive impulses being sent back to count out the tens register. The final finder FF now advances to the wanted group after which the control finder switch continues to advance to a position corresponding to the wanted line. During this movement the final finder FF follows the control finder switch and a revertive impulse is sent back to the units register for each position through which the control finder switch is advanced.

In addition to controlling the tens and units selection the final control circuit determines whether or not the called number is an individual line or a private branch exchange group. Provision is made for P. B. X. hunting by providing the cut-off relays of all the lines of a P. B. X. group except the last line with an additional contact over which an engaged potential is applied to a corresponding terminal in the arc of the control finder FCF when the line is busy. In case the called number corresponding to a P. B. X. group and the first line is found busy the control finder FCF causes the advance of the final finder FF until a free line is found. In case all the lines of the group are found busy the usual busy tone is transmitted to the calling party.

It should be noted that the control circuits are not engaged until the register circuit is ready to receive the corresponding revertive impulses. By this means the control circuits are held in use for the shortest possible time which has been found to average 1-3 seconds (including restoring time) except when all the trunks of a wanted group are found busy. In the latter case the group finder switches are arranged to continue hunting for a predetermined time, say 10 seconds. If a free trunk is not found within this time the

register circuit applies busy tone to the calling line.

It will also be seen that a control circuit finder has a dual function. It is advanced from a normal position and causes the attachment of a predetermined associated group or final finder switch and afterwards it controls the setting of this group or final finder switch. For example, there are usually 10 associated finder switches in a group served by one control circuit. If finder No. 6 has been selected from a preceding switching stage the control circuit finder advances and when position 6 is reached this group finder is attached. The control finder then continues to advance and sends back the revertive impulses.

All the switches in the talking circuit are of the non-homing type and on release of the connection remain in the positions to which they were last set.

The register circuit RC is arranged to handle two digit special service calls for which the numbers 01, 02 etc., are reserved. Such calls are extended to an operator's position over a regular first group finder such as 1GF and a special second group finder such as SGF controlled by a control circuit SCF. The transmission bridge at the link circuit 2LF, 1GF is removed on such calls and the calling line is connected metallically direct to the manual cord circuit from which battery for talking is supplied. Such a connection remains under the control of the operator and the automatic subscriber cannot release until the operator breaks down the connection.

False calls are also automatically extended to a false call operator's position over two group selecting stages. The number 00 is assigned to false calls the register circuit being automatically set to these digits by grounded lines or failures to dial within 30 seconds. When a false call is extended the current bridge is automatically removed from the link circuit so as not to heat the bridge relay. The operator by depressing a key can flash a guard lamp in the link circuit 2LF, 1GF to indicate the finder which is held by the false call.

The system is designed to be built up in vertical bay units. The circuits on each unit will be completed in the factory, all exterior connections being brought out to terminal strips at the top of the unit, the terminal strips of the various units only requiring to be interconnected by cables during the installation of the system. Each unit will be assembled, wired and tested in the factory. The system described may for example be manufactured in the units specified below. The identification numbers of the units are shown on Fig. 12 to indicate how the system could be built up from the standardized units about to be described: The terminal strips for exterior cabling are indicated T in this figure.

Unit No. 1

This unit comprises the subscribers' line circuits, the first line finder circuits and the final finder and final finder control circuits for a group of 100 lines. It is made up of two vertical bays the finder switches being mounted on one bay and the relay groups on the other. The finder switch bay has for example a capacity of 28,100-point finder switches which may be allotted as follows:— 14 first line finders, 12 final finders and 2 final control circuit finders. On the relay bay are mounted the line and cut-off relays for the hundred subscribers' lines, the relays of the line finder circuits and the relays of the final finder and final control circuits.

Unit No. 1A

This comprises a group of second line finders and associated relays.

Units No. 2A

Each of these units comprises group finder circuits and control circuits and is assembled on one vertical bay with a capacity of, say 20,100-point group finder switches and two 50-point control circuit finder switches. On the same bay are mounted the associated relay groups. Each group of 20 group finders is sub-divided into two groups of 10 which are each served by one control finder circuit. The group finders are provided with 5 brushes. These units are used for the regular first group selecting stage and for the special service second group selecting stage.

Unit No. 2B

This unit is similar to unit No. 2A but the group finder switches are provided with 4 brushes only. These units are used for the regular second group selecting stage.

Unit No. 3

This unit comprises register circuits and is made up of three vertical bays with a capacity of 16 register circuits which serve 100 line finder links. The 16 register finder switches and 16 time alarm switches are mounted on the centre bay of the unit. On each of the two outside bays are mounted eight sets of digit switches and 8 sets of relays.

The switch racks may be made up in small units each provided with a driving motor and suitable means whereby the motor is only run when it is necessary to advance a switch of the unit: During busy hours provision may be made for running the motor continuously. A call will now be followed out in detail.

On a subscriber removing his receiver to make a call the line relay L_r , Fig. 1, is energized over the calling loop. Relay L_r places a battery potential on the first line finder test

multiple d and closes a circuit for a common starting relay F_{sr} which energizes the auxiliary starting relays A_{sr} . Relays A_{sr} close circuits for the clutch magnets PF of all free first line finders in series with relay L_{gr} via contacts L_{hr2} , L_{tr2} . If there are no free finders in the group relay L_{gr} remains de-energized and a guard lamp L_{GL} lights.

When a finder, say the one illustrated, reaches the calling line, test relay L_{tr} operates over its high-resistance right-hand winding, opens at contacts L_{tr2} the circuit of magnet PF and at contacts L_{tr1} closes a circuit for relay L_{hr} over its right-hand winding and the common start relay C_{sr} , Fig. 2, of a sub-group of second line finders. Relay L_{tr} also connects battery to the second line finder test multiple d . Relay L_{hr} at contacts L_{hr1} connects the low resistance left-hand winding of relay L_{tr} in parallel with its high-resistance winding to cause the re-lapse of relay F_{sr} which de-energizes the relays A_{sr} to arrest the other first line finders.

Figure 2 shows the starting circuit for the second line finders of a complete group of 52 second line finder circuits in the exchange. This particular group is divided into 5 sub-groups each sub-group normally serving a particular group of first finders but arrangements being provided whereby if all the finders of the associated sub-group are busy those of the next sub-group are set in rotation and so on.

The starting relays are associated with the busy relays E_{cr} , $1E_{cr}$, $2E_{cr}$ of the control circuits. These relays, which are energized over off-normal contacts N of the control circuit switches, are for convenience shown in Fig. 2.

When a call is created from a first line finder circuit, the calling potential operates the C_{sr} relay of the sub-group as already described and the latter relay over its front contact connects a ground to the armature of the over-change contact of the E_{cr} relay, controlled by the particular control circuit which serves this group of group finders. If the control circuit is free relay E_{cr} is de-energized and therefore relay H_{sr} becomes operated; the latter relay operates three other starting relays B_{sr} in parallel, so closing the circuit for the 10 power magnets and for the high resistance windings of 10 test relays. It is, of course, understood that only the finders which are free rotate.

The control of the high resistance windings of the test relays by the starting circuit is needed to avoid shunting out of the test potential by the test relays of other sub-groups which may stay on the calling line; the latter test relays not having their windings grounded are not able to set up a call. If the control circuit is engaged, the starting relays of the sub-group will not be operated, because the front contact of relay C_{sr} is directed by the

overchange contacts of relay Ecr to the slow acting relay Abr which closes a circuit for the Hsr relay of the next sub-group provided the associated control circuit is free. If the 5 second control circuit is not free, the call will be transferred to the following sub-group starting circuit relay, and so on until a free control circuit is found.

If all control circuits serving the complete 10 group of line finder circuits are busy, the lamp SGL will be lit over front contacts in series of all the Abr relays.

If the control circuit of the group is free, but all the line finders are engaged, the pilot 15 relay Sgr will not become operated when relay Hsr is energized, and therefore slow-acting relay Abr will operate and the following 20 sub-group of starting relays will be operated in a similar way to when the control circuit itself is busy.

The group of the line finder circuits may not always be a perfect multiple of 10; therefore, the bottom starting scheme shown on the drawings is made to indicate how to connect the surplus finders of the group in the starting circuit.

There will exist in the exchange a control 30 circuit, which may serve particularly the surplus group finders for all existing line finder groups. For the better understanding of the method, it is supposed that a complete group of line finder circuits is 52. The last sub-group of starting circuits may therefore serve 35 12 line finders instead of 10: the first 10 belonging to the normal control circuit and the remaining two belonging to the surplus control circuit. The relay $2Ecr$ of the latter control finder circuit controls another relay $Ecr1$ with as many back contacts as there are 40 groups of surplus group finders. Each back contact will control one or two starting relays $Hsr1$, which close the circuits of the power magnets of the line finders and the high resistance winding of the test relays of the 45 surplus line finder circuits.

The pilot relay $1Sgr$ is common to the 12 line finders, and this starting circuit operates as follows:

50 Csr being operated, the latter relay operates the $1Hsr$ and $Hsr1$ relays provided the two control circuits are free; if the control circuit for the first 10 is engaged and the control circuit for the surplus finders is free, 55 only the free surplus finders will rotate; or if the surplus control finder is engaged and the other control circuit is free, only the free finders out of the first 10 line finders will rotate.

60 If the control circuits are free, the pilot relay Sgr will operate as long as one of the 12 line finders is free, and in the case of all being engaged, or the two control circuits being busy, relay $1Abr$ will operate and the 65 first sub-group of finders will be put in action

the relay Hsr being energized over contacts of relays $1Csr$, $1Abr$ and Ecr .

If the group of the line finders comprises more than two surplus circuits, for example 6, the starting circuit may be split into two 70 subgroups of 18 each, and not into a group of 10 and another group of 16, because it is not desirable to provide more than 18 finders common to one pilot relay, in order to avoid overheating of the latter relay.

75 Assuming the control circuit associated with the first sub-group of 2nd line finder links is free and that the second finder link comprising the second line finder, Fig. 3 and first group finder, Fig. 4, is also disengaged, the driving magnet PL , Fig. 3 is energized in a circuit extending over relay Sgr , Fig. 2, contacts $3Hsr$, wire 1, and contacts $3Ar1$, $3Dr6$, $3Hr3$ and $3Fr1$.

80 The finder rotates and on reaching the first line finder which has picked up the calling line the relay $3Ar$ becomes energized in a circuit from ground, contacts $5Hsr$, Fig. 2, wire 2, left-hand winding of relay $3Ar$, brush and terminal d of the finder to battery over contacts $Ltr1$.

85 Relay $3Ar$ opens the circuit of magnet PL at contacts $3Ar1$ and causes the energization of relay $3Cr$ from battery over contacts $3Ir1$, $3Ar2$. Relay $3Cr$ at contacts $3Cr1$ connects 90 the low-resistance right-hand winding of relay $3Ar$ to ground, causing the relapse of relay Csr , Fig. 2, provided there is no other call existing at this instant in the same group. Relay $3Cr$ also at contacts $3Cr2$ closes a circuit for relay $3Br$, which operates slowly and over contacts $3Br1$, $3Gr4$ and $3Fr6$ energizes relay $3Dr$. The time $3Br$ and $3Dr$ take to operate covers the danger of a double test. Relay $3Dr$ closes a locking circuit for relay $3Cr$ via contacts $3Dr1$, $3Fr2$, $3Cr3$, and at 100 contacts $3Dr2$, $3Dr3$, extends the a and b wires to the line relay $3Asr$. Relay $3Dr$ also energizes relay $3Hr$ which at contacts $3Hr2$ grounds the c wire causing the energization of the cut-off relay Cor , Fig. 1, over the left hand low-resistance winding of relay Lhr which remains operated over this circuit. Relay Cor disconnects the line relay Lr which opens the circuit of relay Ltr . Meanwhile relay Csr , Fig. 2, has de-energized and opened the circuits of relays Hsr , Bsr thereby stopping further hunting.

110 Relay $3Ir$, Fig. 3 is energized over contacts $3Cr4$, $3Hr4$ and locks up over contacts $3Ir3$, $3Fr5$, $3Gr4$, $3Br1$. When relay $3Asr$ operated it closed another circuit via contacts $3Asr2$ for relay $3Br$ which being slow-to-release is maintained during dialling impulses.

115 Relay $3Ir$ at contact $3Ir2$ applies battery via contacts $3Cr5$ to the leads 3 and 4 to energize the register starting circuit relays Ar , Fig. 10 and to apply test potential to the test contacts in the banks of the register finders.

The register starting relays A_r energize starting relays B_r which close circuits for the clutch magnets PM of register finders associated with free registers: In the register circuit shown this circuit extends from battery, over magnet PM , contacts $Er2$, $Br4$, $Tr1$ to ground. The test relay Tr of the first finder which reaches the calling line finder circuit energizes over its left-hand high-resistance winding via contacts $Dr1$, normal contacts and brushes d of all the digit registers to ground, opens the circuit of magnet PM at contacts $Tr1$ and at contacts $Tr2$ connects its low resistance winding in series with relay Sh_r to mark the link busy to other finders. Relay Sh_r which is of the slow-release type and guards for double test, closes a circuit for relay Er which closes a circuit over the primary winding of the tone coil TC , from battery, over the winding of the magnet PM , contacts $Er3$, $Gr3$, $Fr2$, to the dial tone lead D , and applies dial tone to the calling line over the following circuit:— secondary winding of the tone transformer TC , small condenser $MF1$, contacts $Rv6$, windings of relay Pr , contact $Er6$, register finder wiper b , contact $3Lr5$, $3Er3$, Fig. 3, b wire bridge condenser, calling loop, a wire bridge condenser, contacts $3Er1$, $3Lr4$, register finder wiper a , Fig. 10, contact $Er5$ back to the tone transformer winding.

The calling party now dials the first or thousands digit of the wanted number, thereby intermittently opening the circuit of relay $3Ar_s$, Fig. 3, which at each relapse closes an impulse circuit for relay Ir and Hr Fig. 10, via contacts $3Asr1$, the finder brush d and contacts $Er4$. At each energization of the impulse relay Hr a circuit is closed over contacts $Hr1$, $Jr2$ for the stepping magnet $SW1$ of the thousands digit register. Relay Ir energizes on the first impulse and being of the slow-to-release type remains operated during impulsing. As soon as the thousands digit register reaches the first terminals set the following circuit is closed for relays $3Er$, Fig. 3 and Ur , Fig. 10:— battery, contacts $3Dr1$, Fig. 3, lower winding of relay $3Er$, register finder brush e Fig. 10, contact $Fr1$, low resistance winding of relay Ur , brush b and first terminal of first digit register, contacts $Dr3$ to ground. A locking circuit for these relays is closed via contacts $Ur1$, $Dr3$. Relay Ur also closes a holding circuit for relay Er via contact $Ur2$.

Relay $3Er$, Fig. 3, disconnects the dial tone, and at contact $Er2$ opens the locking circuit of relay $3Cr$, which removes the test potential from the contact engaged by brush e of the register finder, thereby de-energizing relays Tr and Sh_r , Fig. 10. Relay Er , Fig. 10, however remains held via contacts $Ur2$ as already explained. At the end of the first impulse series, relay Ir relapses and closes a circuit for relay Jr via brush a of

the thousands digit register. Relay Jr closes a circuit for relay Gr via its contacts $Jr1$ and parallel thereto a circuit for relay Kr via contacts $Gr2$, $Fr6$, locks to contacts $Er1$, and at contact $Jr3$ transfers the impulsing circuit via contact $Lr3$ to magnet $SW2$ of the hundreds digit register. Relay Gr is slow-to-operate and before operating ensures the operation of relay Kr which locks up over contacts $Kr3$, $Nr1$, $Er1$. When the subscriber sends the second series of impulses the magnet $SW2$ of the hundreds digit register responds and the register takes up a position corresponding to the digit dialled. On the cessation of these impulses relay Lr becomes energized and transfers the impulsing circuit to the magnet $SW3$ of the tens digit register via contacts $Lr4$, $Scr3$, $Or5$. The third series of impulses advances this register and when the last impulse is received relay Or energizes and transfers the impulsing circuit via contacts $Or4$ to the magnet $SW4$ of the units digit register which responds to the last series of impulses.

When relay Kr operates at the end of the first digit it connects ground to the b wire of the fundamental circuit via contact $Kr4$, winding of the outstepping relay Pr , contacts $Er6$, and the register finder brush b , and connects battery to the a wire of the fundamental circuit via a resistance, contacts $Kr5$ and the register finder brush a .

The connection of battery to the a wire closes a circuit for the common starting relay Aer , Fig. 7, of the first group finder control circuit via contacts $3Ir4$, $3Cr6$, Fig. 3 and $J2r3$, Fig. 4 and places a potential on the contact of the level wiped over by brush i particular to the engaged second finder link.

It will be convenient here to describe the arrangement of the bank contact of the group finder control circuit switches. These have 51 points or positions (the first being used as a home position) and five levels of contacts wiped over by brushes $f-j$. The ten contacts in the first ten positions in levels h and i are wired to the ten first group finders controlled by the control circuit. The remaining 40 points in these two levels are not used. Points 11 to 50 are used for reverting control and in levels f and g are divided into ten groups of four each. In level g the second and third contacts of each group of four are strapped together and grounded. The fourth contact of each group of four in level f as 14, 18, 22, etc. is wired to the marking terminals t of its corresponding group of junctions outgoing from the group finder switches. The marking wires are connected to terminals $f1$, $f2$, $f3$, etc., on a small terminal strip from which jumping wires are taken to the group finders. The 100 out junctions, the normal capacity of the group finders, may be divided into ten groups of 130.

different sizes, providing the total remains 100. The *d* terminals of all the outjunctions of the first group are wired to the first terminal *f*1 in level *f* of the control switch, all 5 those of the second group to the second *f* terminal *f*2 and so on. All the junction groups may comprise 10 junctions each or some groups may be larger and others smaller. As the group finders have no home 10 positions the junctions in each group may be distributed in any order around the arc so as to reduce hunting. Where ten junction groups are not required the finder arcs may be divided into fewer groups. The contacts 15 in the level *j* are grounded and are used for centering the brushes.

Resuming now the operation of the system, the start-relay *Acr*, Fig. 7 when energized closes a circuit over contacts *Fcr*2 and *Bcr*1 20 for the power magnet *PC* and the control finder switch is rotated. A circuit is now closed over off-normal contact *N* for relay *Ecr*, Fig. 2, which prevents hunting of all the second line finders belonging to the sub- 25 group served by the control circuit. When the predetermined group finder is reached, the test relay *Bcr* operates to the battery on the test contact, the power magnet *PC* is disconnected and the following circuit is closed 30 for relays *Fcr*, Fig. 7, and *Jir*, Fig. 4:—battery windings of relays *Fcr* and *Jir*, contact and wiper of level *h*, contacts *Bcr*2, *Ecr*2, off-normal contacts *N* to ground. Relays *Fcr* and *Jir* lock to ground at contacts 3 *Br*1, Fig. 35 3, via contacts *Jir*2, *J2r*2 and the *c* wire and at contact *J1r*1 relay *Jr*1 connects the *b* wire of the fundamental circuit to relay *Dcr* of the control circuit. Relay *Fcr*, Fig. 7 operates slowly and does not open its contacts *Fcr*2 40 until relays *Jir* and *Dcr* energize. The out-stepping relay *Pr* in the register now energizes in series with relay *Dcr*, Fig. 7. Relay *Pr* closes at contact *Pr*1 a circuit via contacts *Mr*4 for relay *Rr*, which closes a circuit 45 for relay *1Rr* over contacts *Rr*3 and wiper *C* of the first digit register providing that the switch is in one of the positions 1 to 9. This locking circuit is not closed if the switch is in position 10. Relay *1Rr* closes a 50 holding circuit for relay *Rr* over its contact *1Rr*1. Relay *Rr* closes an obvious circuit for relays *Nr* and *Sr* and at contact *Rr*5 connects the outstepping relay *Pr* in a metallic circuit across the *a* and *b* wires of the fundamental circuit. Relay *Bcr* Fig. 7 now 55 relapses being unable to operate in series with relay *Dcr*. Relay *Nr* opens the locking circuit of relay *Kr* at contacts *Nr*1 and holds over contacts *Sr*2, *Nr*2, *Er*1. In the control 60 circuit, relay *Dcr* closes the following circuit for the power magnet *PC* of the control finder switch:—ground, off-normal contact *N*, contacts *Fcr*1, *Dcr*2, *Ger*4, winding of magnet *PC* to battery. The control switch 65 now advances its brushes over the remainder

of the ten calling junction positions and in its further advance each time the brush *g* passes over a grounded group contact the outstepping relay *Pr* of the register is short-circuited for an instant. At each relapse 70 of relay *Pr* a circuit is closed via contacts *Pr*2 and *1Rr*2 for relay *Qr* which closes a circuit from ground at springs of key *RK* via contacts *Qr*2 and brush *f* of the thousands digit register for the magnet *SW1* thereof 75 and locks up via contact *Qr*1 and brush *e* of this register to the grounded interrupter contacts *I* of the magnet *SW1*, thus maintaining the circuit of magnet *SW1* closed even if relay *Pr* should open its back contact 80 before magnet *SW1* is fully energized. In this manner the thousands digit register is advanced until it reaches position 10 in which the circuit of relay *1Rr* is opened. Relay *1Rr* opens the holding circuit of relay *Rr* 85 so that at the next de-energization of the out-stepping relay *Pr*, relay *Rr* relapses and at contact *Rr*5 opens the fundamental circuit. Relay *Sr* is now deprived of current and de-energizes relay *Nr*. Both these relays are 90 of the slow-to-release type and whilst relay *Nr* is falling away the following circuit is closed for relays *Mr* and *Qr*:—ground contacts *Er*1, *Nr*2, *Sr*1, brush *c* of thousands digit register, left-hand winding of relay *Mr* 95 and winding of relay *Qr* to battery. Relay *Qr* recloses the circuit of magnet *SW1* which advances the first register to its normal position whilst relay *Mr* recloses the fundamental circuit at contacts *Mr*5 and locks over its 100 right-hand winding and contacts *Pr*1 of relay *Pr* which is again energized over the fundamental circuit. If the first digit register is set to position 10 the relay *1Rr* relapses on the first de-energization of the out-stepping relay *Pr* and the operation proceeds as described above. 105

During the opening of the fundamental circuit at the register between the relapse of relay *1Rr* and the response of relay *Mr*, 110 relay *Dcr*, Fig. 7 in the finder control circuit de-energizes and closes a circuit for relay *Gcr* extending from ground at off-normal contacts *N* via contacts *Fcr*1, *Dcr*3 and *Ger*3. Relay *Gcr* locks over contacts *Ger*2-3 115 and connects ground via contacts *Ger*6, the high-resistance right-hand winding of test relay *Hcr*, brush *f* and the engaged marking terminal, to all the *d* terminals of the group of junctions corresponding to the first digit 120 dialled by the subscriber. The power magnet *PJ*, Fig. 4 of the group finder also receives ground over contact *Ger*5, *Hcr*1 and *J1r*3 and the group finder rotates. As its brushes *c* and *t* are connected together over front contacts *J1r*5, when a free trunk in the wanted group extending to an idle second group finder the associated control circuit of which is also idle, is reached, the test relay *Hcr* in the control circuit energizes from the bat- 125 130

tery connected to the *c* wire of the junction. Relay *Hcr* opens the circuit of magnet *PH* and connects a low-resistance test relay *Scr* and its own low-resistance left-hand winding parallel with its high-resistance right-hand winding thereby busying the seized junction to other calls. Relay *Scr* closes a circuit via contacts *Scr1* and *Jlr4* for the group finder relay *J2r* which locks to the 10 grounded front contact *3Br1* of relay *3Br*, Fig. 3 in the link circuit. Relay *Scr* operates slowly to guard against double connections. Relay *J2r* completes at contacts *J2r4* and *J2r5* the through connection from the line finder circuit to the seized junction and opens at contacts *J2r2* the locking circuit of relay *J1r* which releases thus disconnecting the group finder from the control circuit. Relay *Fcr* is also deprived of current when 20 relay *J2r* energizes, opens the holding circuit for relay *Gcr* and closes a restoring circuit for the control switch over the off-normal contact *N* and contacts *Fcr2* and *Bcr1*. If the relay *Acr* is energized due to another junction 25 being in a calling condition, the switch will continue rotating and the second junction will become immediately attached.

Returning now to the register, when the relay *Ir* energizes after the recording of the 30 second or hundreds digit, a further circuit is closed for relay *Kr* which extends from battery, contacts *Fr6*, right-hand winding of relay *Kr*, contact *Lr6*, brush *b* of hundreds digit register, and contacts *Mr1*, *Nr1*, *Er1* to ground. Relay *Kr* re-connects battery to the *a* wire and energizes the starting relay *8Acr*, Fig. 8 of the control circuit of the second group finder, and re-connects ground through the outstepping relay *Pr* to the *b* wire. It 40 will be seen therefore that if a second group finder is taken into use before the hundreds digit has been completely recorded, the control circuit is not attached until the register is ready to receive the reverting impulses. 45 On the other hand if the register becomes ready to receive the reverting impulses before a second group finder has been seized or before a control circuit has become attached to a seized second group finder, relay *Kr* will be re-energized immediately relay *Mr* relapses on the de-energization relay *Pr* when the fundamental circuit is opened 50 on the first group finder engaging a free junction with the aid of its control circuit, and will therefore cause the attachment of a second group finder control circuit at the earliest possible moment.

A second group finder is shown in Fig. 5 and its control circuit in Fig. 8 but since 60 the operation of these circuits is similar to that of the circuits illustrated in Figs. 4 and 7 it is only necessary to describe briefly the operations at the second group selecting stage. The starting relay *8Acr* closes a circuit for 65 the control circuit driving magnet *8PC* which

advances the control switch wipers to the calling junction, on which magnet *8PC* is de-energized and the group finder relay *5J1r* energizes in series with the control circuit relay *8Fcr*. Relay *SEcr* also operates and disconnects from the common lead to mark the control circuit and its associated second group finders non-selectable. Relay *5J1r* attaches the control circuit. The register outstepping relay *Pr* now energizes in series with the control circuit relay *8Dcr* over the *b* wire of the fundamental circuit, the control switch is again rotated and revertive impulses are sent back to the register circuit to count out the hundreds register switch. The fundamental circuit is then momentarily opened at the register circuit, the control circuit relay *8Dcr* de-energizing and energizing relay *8Gcr*, which connects up the test relay *8Hcr* and closes a circuit for the group finder power magnet *5PJ*. The group finder hunts in the marked group and when a free junction is found relays *8Hcr*, *8Scr* and *5Jcr* energize, completing the connection to the final finder. Relay *5J2r* opens the circuit of relay *5J1r* which disconnects the control circuit. Relay *8Fcr* relapses and closes a circuit for the magnet *8PC* which drives the control switch to normal or to another calling junction. The fundamental circuit is 85 opened and the register relays *Pr* and *Mr* de-energize.

Providing that the fourth or units digit register switch has moved to its first position, that is, that at least one unit impulse has been received by the register, a circuit is again established for the relay *Kr* this circuit extending from battery, contacts *Fr6*, right-hand winding of relay *Kr*, brushes *b* of the units and tens registers, and contacts *Mr1*, *Nr1*, *Er1*, to ground. Relay *Kr* re-connects battery to the *a* wire of the fundamental circuit and ground to the *b* wire through the outstepping relay *Pr*. The starting relay *9Acr*, Fig. 9 of the fundamental circuit and energizes relay *9Ecr* which removes battery from the common lead to busy all the associated junctions as long as the common circuit is in use.

It will be convenient here to describe the arrangement of the bank contacts of the final control circuit switches. These switches have a capacity of 102 points arranged in two semi-circular arcs of 51 points each. The finders have six sets of brushes as shown. The normal contact *N* closes whenever the switch leaves its home position and is not opened until the wipers have made a complete revolution through 360° . The lines in the upper and lower levels of *e* and *f* are numbered as indicated. The extra position *H* and *H¹* in each level is located where indicated.

The two levels *e* are used as described subsequently for P. B. X. hunting. These two levels are wiped over by two connected single-

130

ended brushes arranged 180° apart, one brush wiping over the upper 51 terminals during the first half revolution and the other brush over the lower 51 terminals during the second half revolution. The terminals in positions H and H' are dead.

The two levels f are wired to the marking contacts d of the final finders and are arranged in the same manner as the levels e .

10 Level g comprises five wide segments occupying positions 8-9, 18-20, 29-30, 39-40 and 49-50 respectively. These segments are wiped over by a double-ended brush twice during each complete revolution 15 and the grounding of the fundamental circuit takes place over them. The segment immediately preceding the positions H and H' is one position longer than the others since the brushes have to take an extra step over 20 these contacts to reach the beginning of the next group.

The levels h and i each contain 10 terminals occupying positions 1-10 in the first half revolution. These levels are wired to the 25 final finder circuits, there being, therefore, capacity for 10 final finders in each group: This number however may be varied according to requirements. These levels are wiped over by two single brushes and are therefore 30 wiped over but once during a complete revolution of 360° .

Level j consists of a series of grounded terminals wiped over by a double-ended brush. These terminals are used to centre the 35 control finder brushes.

As the control finder may pick up a final finder between positions 1 to 10 it is necessary that the segment in positions 8 and 9 in level g be insulated until the brush commences on its second half revolution. The reverting count is therefore commenced on the segment in positions 18-20 and the contacts in levels e and f are numbered accordingly. The first engagement of this segment by brush g causes the energization of relay $9Fcr$, which grounds the first segment (in positions 8-9) during the remainder of the selective operation.

Resuming the circuit operation, relay $9Acr$, 50 Fig. 9 closes a circuit for the power magnet $9PC$ via contacts $9Acr1$, $9Dcr1$, $9Fcr7$, and $9Bcr1$. The brushes rotate and when the calling junction terminals are reached relay $9Bcr$ is energized over brush i and the a wire of 55 the fundamental circuit, opens the circuit of the magnet $9PC$ and completes the following circuit:—ground, off-normal contacts N , contacts $9Dcr1$, $9Fcr7$, $9Bcr2$, brush h , winding of relay $F1r$, Fig. 6 and common lead to battery. Relay $F1r$ energizes locks over contacts $F1r3$, $F3r5$, $F2r7$ and the c wire to 60 grounded contacts $5J2r1$, Fig. 5 and closes a circuit over the b wire of the fundamental circuit for the outstepping relay Pr in the register circuit and for relay $9Der$ in the con-

trol circuit. Relay $9Der$ recloses the circuit of the power magnet $9PC$ via contacts $9Ger3$ and $9Der2$. Relay $9Fcr$ at contacts $9Der4$ grounds the last four group contacts in the bank g and the first ten centering contacts in the bank j . When the brush g engages the first grounded group contact (positions 18-20) a circuit is closed over contacts $9Ger5$, $9Der3$, $9Fcr2$ for relay $9Fcr$ which locks over contacts $9Fcr3$ in parallel with relay $F1r$, Fig. 6 connects the brush g to the b wire of the fundamental circuit via contacts $9Ger5$, $9Der3$, $9Fcr1$ and $F1r1$ and grounds the first reverting group contact via contacts $9Ecr3$ and $9Fcrb$. As will have been appreciated from the preceding description this contact occupies positions in the arc allotted to the calling junctions and the sending of reverting impulses must not begin until after the control switch has passed beyond this group in order that the first reverting impulse shall always be sent back from the same position on the control switch arc no matter whether the first or last final finder is selected. The control switch continues to rotate and for every ten steps a reverting impulse is sent over the b wire to count out the tens register in a similar manner to that previously described with reference to the thousands register.

When at the end of the last short-circuit impulse brush g leaves the grounded terminal the switch will stop on the next terminal f because the centering brush j will be connected to ground over a centering terminal before the brush g leaves the impulse contact.

In the register circuit when the tens register arrives in position 10, on the next relapse of relay Pr , relay Rr falls away and opens the fundamental circuit. Relay Rr opens the circuit of relay Sr and between the relapse of the relays Sr and Nr the following circuit is closed:—battery, winding of relay Qr , brushes c of the tens hundreds and thousands register, contacts $Sr1$, $Nr2$, $Er1$ to ground. Relay Qr steps the tens switch to its normal position. Relay Kr is immediately energized over its left-hand winding via brushes b of the tens and units registers, and contacts $Mr1$, $Nr1$, $Er1$ provided the last digit has been received and relay Ir has relapsed and at contacts $Ir2$ removed the short circuit from the left hand winding of relay Kr . Relay Kr closes the fundamental circuit for the units selection and relay Pr causes the reoperation of relays Rr , $1Rr$, Sr , Nr . Relay Qr now relapses.

When the fundamental circuit is opened at the register circuit, relay $9Der$ is de-energized, opens the circuit of the power magnet $9PC$ at contacts $9Der2$ and closes a circuit via contacts $9Der1$, $9Fcr6$ and $9Ger2$ for relays $9Ger$ and Icr in parallel. Relay $9Ger$ locks over contacts $9Ger1$, $9Ecr3$, and

9Fcr5, prepares a circuit for the test relay 9Her at contacts 9Gcr6 and closes a circuit via contacts 9Gcr7, 9Her3, 1Cr3 and F1r7 for the final finder power magnet PF. The control switch stops on the last terminal set of the preceding group of ten lines the reason for this being that when the units selection is made the switch always makes one step. The contacts in level f of the control switch 10 are connected to contacts d in the banks of the final finders and when the final finder reaches the marked terminal d the following circuit is completed for the test relay 9Her:— battery, winding of 9Her, contact 9Gcr6, brush f of control switch terminal d and brush of final finder, contact F1r4 to ground. Relay 9Her opens the circuit of power magnet PF.

Meanwhile the fundamental circuit is 20 closed at the register circuit and relay 9Der again energizes and closes a circuit for relay Ycr as follows:—battery, winding of relay Ycr, contacts Ycr4, 9Gcr4, 9Der2, off-normal contact N to ground: Relay Ycr locks via 25 contacts Ycr3, 9Ecr3 and 9Fcr5. Relay Ycr is made slow to energize in order to allow the stepping relay Pr in the register to energize and a helping relay Rr to energize over its front contact before relay Lcr energizes. 30 Providing that the test relay Her has by this time energized a circuit is completed for relay Lcr via contacts 9Her1, Mcr3 and Ycr2. Relay Lcr grounds the b wire of the fundamental circuit at contacts Lcr1 and closes a 35 circuit for the control switch power magnet 9PC via contacts Lcr2, 9Her2, 9Gcr7. Magnet 9PC advances the switch and holds over the centering terminal on level j. When the brush on level f leaves the terminal on which 40 it is standing relay 9Her relapses and opens the circuit of relay Lcr which removes the ground from the b wire of the fundamental circuit and recloses the circuit of the power magnet PF of the final finder which advances 45 to its next position in which relays 9Her and Lcr again energize. In this manner reverting impulses for the units selection are sent back from the final control circuit to the register circuit, the final finder making one 50 step for each impulse.

In the register circuit the reverting impulses are repeated as before by relay Qr to the units register magnet SW4. In position 10 of this register switch, relay Rr is unlocked on the next relapse of relay Pr. Relays Sr and Nr are de-energized and before relay Nr has time to relapse a circuit is closed for relay Dr via brushes e of all the register switches and contacts Sr1, Nr2, Er1. Relay 55 Dr locks up over contact Dr4 and opens at contacts Dr3 the circuit of relay Ur. Relay Ur opens the locking circuit of relay Er which in turn unlocks all the operated relays in the register circuit excepting relay Dr. Relay Dr also closes a circuit for relay Qr

via contact Dr5, brushes e of all the registers and interrupter contacts of magnet SW4. Relay Qr closes a circuit to step the units register into its normal position. Relay Qr releases immediately the units register steps 70 out of position 10, but in the normal position is again energized over contacts Dr5, the brushes e of the registers and contacts Dr4. A check is made that all the register switches are at normal and a circuit is then closed via 75 contacts Qr2 and all the brushes f for short circuiting relay Dr. An exchange attendant by throwing key RK can close a circuit for relay Dr to restore the register circuit. Progress lamps 1L, 2L, 3L are lighted in parallel 80 over the locking circuits of relays Jr, Lr, Or and lamp 4L over the off-normal bank a of the units register to indicate the progress of the setting of the register circuit.

Returning now to the final control circuit 85 when the register is counted out the fundamental circuit is finally opened in the register circuit relay 9Der deenergizes and the following circuit is closed for relay Mer:— battery, winding of relay Mer, contacts 90 Mer5, Ycr5, 9Fcr6, 9Der1, off normal contacts N to ground. Relay Mer locks up via contacts Mer6, 9Ecr3, 9Fcr5, disconnects relay Lcr at contacts Mer3 before it has time to operate again, at contact Mer4 closes a 95 circuit for relay Xcr via contacts Per1, 9Her1 and in parallel thereto via contacts Icr2 for slow-release relay Jcr. Relay Xcr locks over contacts Xcr4, 9Ecr3, 9Fcr5 and at contacts Xcr2 connects ground via contacts F1r6 to 100 the test relay Ftr Fig. 6 and at contacts Xcr6 opens the circuit of relay Icr which commences to release and on closing its contact Icr1 opens the circuit of slow-release relay Jcr and short-circuits the winding of relay 105 Ycr over contacts Mer4 and 9Her1. Relay Ycr releases. At the moment of testing a holding ground is given to relay F1r, Fig. 6 via contacts 9Der1, 9Fcr6, Xcr5, Jcr1, 9Gcr6, control switch brush f, final finder brush d, 110 and contacts F1r4. With relay Ycr de-energized and relay Xcr energized a ground is connected to the winding of relay F3r, Fig. 6 via contacts Ycr1, Xcr1, F1r5. Relay F3r operates and locks over contact F3r3, Frr1. 115 The relapse of relay Jcr after an interval opens the holding circuit of relay F1r which frees the control circuit. It is arranged that the release period of relays Icr and Jcr is sufficient to allow time for testing. 120

If the wanted line is idle, relay Ftr energizes in series with the cut-off relay thereof and closes a circuit for relay F2r over contacts Ftr1 to ground on the c wire. Relay F2r at contacts F2r6 holds relay Ftr. Ringing current is now supplied to the calling line from the ringing source via winding of relay Frr, contacts F2r2, F3r2, F2r5, called line, contacts F2r4, F3r4 to ground. Tell-tale ringing tone is applied to the calling line 125 130

through the condenser MFR. When the called party answers, relay F_{rr} operates and unlocks relay F_{3r}. The called party is now connected through to the link circuit, Fig. 3 where relay 3C_{sr} energizes over the called party's loop and closes a circuit for relay 3Fr to ground at the contacts 3Br₁, via its contacts 3C_{sr1}. Relay 3Fr locks to this ground via contacts 3Fr₄, 3Gr₄ independently of relay 3C_{sr}, unlocks relay 3Ir which disconnects the register. Relay 3Dr remains held over contacts 3Asr₂ of relay 3Asr. The calling and called parties are supplied with talking current over relays 3Asr and 3C_{sr} respectively.

If the called line is busy relay F_{2r} does not become energized and on the response of relay F_{3r}, busy tone from the source BT is transmitted to the calling line via contacts F_{2r1}, F_{3r2} and the condenser MFR.

When the holding circuit of relay F_{1r} is opened this relay relapses and disconnects the control circuit. The relapse of relay 9F_{cr} de-energizes relays 9G_{cr}, 9H_{cr}, X_{cr} and M_{cr}, and a restoring circuit for the magnet 9PC is closed over off-normal contacts N, contacts 9D_{cr1}, 9F_{cr7} and 9B_{cr1}. If the called party hangs up but not the calling party, relay 3C_{sr} relapses and circuit 3Br₁, 3C_{sr2}, 3Fr₃ is closed for a lamp GL over an alarm wire.

When the calling party hangs up relay 3Asr de-energizes and opens the circuits of relays 3Dr, 3H_r, and 3Br. Relays 3Br and 3H_r release slowly. Metering battery is connected to the c wire via contacts 3Fr₂, 3Hr₁ to operate the service meter SN, Fig. 1. When relay 3Br releases, relay 3Fr de-energizes and disconnects the metering battery. Relay 3Br removes ground from the forward c wire causing the relapse in turn of the switching relays J_{2r}, Fig. 4, 5H_{2r}, Fig. 5 and F_{2r}, Fig. 6 at the group and final finders. These switches remain on the junction or line terminals with which they are in engagement. The opening of the c wire thus makes the connection instantly available for a second connection.

Private branch exchange hunting

The level e of the final control finder is used for P. B. X. hunting and the front contacts Cor₂, Fig. 6 of the cut-off relays on all lines in a P. B. X. group except the last are connected to terminals on this level. When the units selection is completed and relay M_{cr} energizes, a circuit is prepared over contacts M_{cr7}, X_{cr3} for relay P_{cr}. Relay P_{cr} operates faster than relay X_{cr} which is slow to-operate and if the wanted number is one of a P. B. X. group and is engaged relay P_{cr} energizes over brush e and contacts Cor₂, opens the circuit of relay X_{cr} at contacts P_{cr1}, and closes a circuit over contacts P_{cr2} for the power magnet 9PC which advances

the control switch a step on the next contact set where relay 9H_{cr} falls off and closes the circuit for advancing the final finder to the next line in the P. B. X. group where 9H_{cr} again energizes. If this line is also engaged relay P_{cr} is again energized and the control switch is advanced a further step. This action is continued until either a free line in the group is found or the last line is reached. On the last line the front contact of the cut-off relay is not connected to the e level and hunting is therefore definitely stopped. The last line is tested in exactly the same way as a single line and if it is engaged the busy tone is given to the calling party.

Special service calls

As previously stated the register circuit is arranged to handle two digit special service calls for which the numbers 01, 02 etc., are reserved. If a first digit "0" is dialled the thousands register switch is stepped to position 10 and on the response of relay J_r a circuit is closed via contacts Dr₃, brush b and contacts Gr₁ for relay Scr which locks over contacts Scr₄-5 to ground at contact J_{r1}. Over contacts Scr₁ and Scr₃ the connections to the tens register are opened, whilst at contacts Scr₆-7 the 10th terminal of the c bank of the hundreds register is transferred from relay M_r to relay Dr. At the end of the second digit relay L_r is energized as in a normal call. The register circuit now controls selection at two group finder stages, at the end of the second selection relay Dr being energized instead of relay M_r over the following circuit:—ground, contacts Er₁, N_{r2} and S_{r1}, brushes c of thousands and hundreds register switches, contacts Scr₆, winding of relay Dr to battery. The energization of relay Dr causes the register circuit to be released as previously described.

The call is directed over a regular first group finder such as that shown in Fig. 4 and a special service second group finder to local trunk to an operator's position. The special service second group finder differs from a regular second group finder in that a fifth brush is provided: Its operation is identical. When a special service trunk is engaged a calling relay at the operator's position is energized over the c wire and lights a calling lamp. The operator plugs in, the connection of earth to the sleeve contact closing a circuit over the d wipers of the special service second group finder and the regular first group finder, and relays 3Er and 3Gr at the link circuit, Fig. 3. Relay 3Gr opens at contacts 3Gr₄ the circuit of the relay 3Dr which disconnects the calling side current bridge. Relay 3Er disconnects the called side current bridge. The calling subscriber is now connected to the operator's position over a metallic circuit including contacts 3Gr₁, 3Gr₂. The cut-off relay of the calling line is

maintained operated by relay 3Hr which is held over contacts 3Gr3. Current for talking and other purposes is supplied direct from the operator's cord circuit. Relays 3Asr and 3Cr are de-energized, whilst relay 3Gr at contacts 3Gr5 maintains relay 3Br energized independently of the calling party to transfer release control to the operator. If the operator should release before the calling subscriber relay 3Gr de-energizes and the circuit of relay 3Dr is again closed and the current bridge connected to the calling line. Relay 3Asr therefore energizes and closes the original circuit for relay 3Br which holds the connection.

Premature releases

Premature releases are characterized by the opening of the loop to relay 3Asr, Fig. 3 and the subsequent relapse of relays 3Br, 3Dr. The connection to the *c* brush of the register finder is thereby opened causing the de-energization of relay Ur, Fig. 10, in the register circuit and the completion of a circuit for relay Dr via contacts Ur3, Gr4. Relay Dr locks over its contact Dr4 and initiates the restoration of all the register switches which are out of normal, by closing the following circuit for relay Qr:—ground, interrupter contacts I of magnet SW1, off-normal arc and brush *e* of the thousands register, contacts Dr5 and winding of relay Qr to battery. Relay Qr at contacts Qr2 connects ground of the brush *f* of the thousands register which goes home. In the home position the thousands register a similar homing circuit is closed for the hundreds register and so on until all the registers are restored and relay Dr is short-circuited over contacts Qr2 and the brushes *f* of all the registers in their home positions. When relay Dr relapses relay Qr is de-energized and the register circuit fully restored.

When relay 3Br, Fig. 3 relapses, ground is removed from the forward *c* wire causing the freeing of the conversation finders which may have been taken into use.

All trunks busy

It will be remembered that relay Mr in the register circuit energizes and locks over the front contacts of relay Pr when a group finder commences its hunt for an idle trunk in a wanted group and is unlocked when the relay Pr de-energizes on the opening of the fundamental circuit when an idle trunk is seized. Relay Nr is de-energized at this time. Relay Mr at contacts Mr1 holds open the circuit of relay Kr and in this condition a circuit is closed for the driving magnet TA of the time switch T via contacts Kr2, Nr1, Er1. If after a predetermined interval, say 10 seconds, an idle trunk has not been picked up and the relay Mr unlocked and relay Kr again operated, when the brush 2 of the

switch T engages contact 1 a circuit is closed via contact Mr2 for relay Fr which locks to grounded contacts Er1. Relay Fr connects busy tone over lead B and contacts Fr3 to the primary of the tone transformer TC in place of dial tone, unlocks relay Mr at contacts Fr6, and by opening contacts Fr1 introduces the high resistance winding of relay Ur in the circuit of relays Ur, Fig. 10 and Er, Fig. 3. Relay Er, Fig. 3 now falls away and busy tone is sent to the calling party over the circuit previously described with reference to the transmission of dial tone. When the subscriber replaces his receiver the register circuit and the talking circuit switches are released as in a premature call. If after the expiry of a predetermined interval the register is not released when the brush 2 of the switch T engages contact 5 an alarm lamp GL is lighted.

During the hunting for a free trunk by a group finder, Fig. 4 or Fig. 5, relay DCr, Fig. 7, or 8Dcr, Fig. 8 of the associated control circuit is maintained operated from the register circuit, but on the expiry of the 10 seconds, when relay Mr is unlocked, relay Dr or 8Dcr is released and closes a circuit for an alarm lamp AL over contacts Ger1, Dr3, Fer1 (or 8Ger1, 8Dcr3, 8Fer1).

False calls

If a bad line creates a call, when a register circuit is attached, on the energization of relay Er, Fig. 10 the following circuit is completed for the driving magnet TA of the timing switch T:—ground, contacts Er1, Nr1, Kr2, winding of magnet TA to battery. After the expiration of a predetermined interval of say 30 seconds the timing switch T advances its wiper 2 to the contact 4 and closes a circuit for relay Xr via contacts Gr5. Relay Xr closes a circuit for the magnet SW1 of the thousands register via interrupter contacts I, contacts Jr6, Xr1, brush *f*, contacts Xr3. The thousands register continues to step over a circuit including strapped contacts 2 to 9 of arc *f* until it reaches position 10 where its circuit is opened, relay Jr energizes over the brush *a* and relay Scr energizes over the brush *b*, locks to contacts Jr1 and maintains the circuit of relay Xr over contacts Scr2. A holding circuit for the time switch magnet TA is also closed via contacts Jr1, Scr5, Lr7 wiper 1 of switch T and contact 3. A circuit is now closed for the magnet SW2 of the hundreds register extending from its interrupter contacts over contacts Lr1, Jr5, Xr1, brush *f* of thousands register, contacts Xr4, brush *f* of hundreds register, contacts Xr6—7. The magnet SW2 continues to step the hundreds register until it reaches position 10 in which its circuit is opened and relay Lr is energized. Relay Lr locks up and opens the holding circuit of the time alarm magnet TA at contacts Lr7.

- In the meantime relay K_r has become energized over contacts $Gr2$, $Jr1$, and selection proceeds as if the digits 00 had been dialled and take place in exactly the same way as a special service connection. The subscriber's line is thereby extended over one of a special group of junctions to a false call position, Fig. 11 where relay $4Br$ is energized and lights the calling lamp SL . Relay $4Ar$ is energized over the brushes d of the first and second group finders in series with relay $3Er$ and $3Gr$, Fig. 3 in the link circuit. Relay $4Ar$ locks to the c wire. Relays $3Er$ and $3Gr$, Fig. 3 remove the current bridges at the line 10 finder circuit as in a special service call and the calling line is metallically connected to the false call circuit, battery and ground being supplied through the windings of relay $4Br$.
- When the false call operator inserts a plug PF in the jack FJ , relay $4Cr$ energizes over the sleeve wire and disconnects relay $4Br$. The subscriber's line is now metallically connected to the false call operator's cord and 15 can be tested for insulation etc. To enable faulty lines to be traced back and plugged out the lamp GL , Fig. 3 can be flashed from the false call position. For this purpose a key FCK is provided which when depressed 20 opens the circuit of relays $3Er$ and $3Gr$, Fig. 2. The operator then depresses a key FK which bridges the talking wires causing the energization of relay $3Gr3$, Fig. 3 which 25 closes the circuit of relay $3Fr$; relay $3Fr$ locks up independently of relay $3Csr$. When the key FK is subsequently vibrated relay $3Csr$ is intermittently energized and flashes the lamp GL . When the line finder circuit has 30 been located, the key FCK is released and the metallic through connection again established. Relay $3Fr$, Fig. 3 is unlocked so that 35 if the fault is cleared the meter will not be operated. The register circuit is restored in the usual manner.
- Claims.
1. In a telephone exchange system, the combination of a plurality of single-motion power driven conversation switches, a plurality of control switches common to said conversation switches, means under the control of said control switches for controlling the operation of said conversation switches, a register controller, means under the control of said register controller for controlling the operation of said control switches, and means under control of said control switches for transmitting revertive impulses to said register controller.
2. In a telephone exchange system, the combination of a plurality of switching stages, a plurality of single-motion power driven conversation switches at each switching stage, control switches each common to a plurality of conversation switches but individual to the switching stage to which said

conversation switches belong, means under the control of a control switch to control the operation of the conversation switches, a register controller, and means under control of said control switch for transmitting revertive impulses to said register controller. 70

3. In a telephone exchange system, the combination of a group of conversation switches, a control switch common to the group of conversation switches for controlling their operation, a common registering and controlling mechanism for registering a wanted number, and means under control of said control switch to transmit revertive impulses to said registering and controlling mechanism to control the operation of said control switch. 75

4. In a telephone exchange system, the combination of a plurality of switching stages, conversation switches at each switching stage, control switches, means under control of said control switches for directly operating said conversation switches, registering and controlling mechanism for recording a wanted number, and means under control of said control switches to transmit revertive impulses to the registering and controlling mechanism at the respective switching stages. 80

5. A telephone system comprising a plurality of selectors, control switches, common to said selectors, and provided with brushes which are adapted to move in the same direction, first to select groups of lines and then a line within a selected group, a registering and controlling mechanism, and means under control of said control switches for sending revertive impulses to said registering and controlling mechanism over their brushes during their movement. 85

6. A telephone system comprising a plurality of selectors, control switches, common to said selectors, and provided with brushes which are adapted to move in the same direction, first to select groups of lines and then a line within a selected group, a registering and controlling mechanism, and means controlled by said control switches for sending revertive impulses over their brushes during the first selecting movement, and a second set of revertive impulses during the second selecting movement to said registering and controlling mechanism. 90

7. A telephone system comprising a plurality of selectors, control switches, common to said selectors, and provided with brushes which are adapted to move in the same direction, first to select groups of lines and then a line within a selected group, a registering and controlling mechanism, and means controlled by said control switches for sending revertive impulses over their brushes during the first selecting movement, and a second set of revertive impulses during the second selecting movement, the means under the control of 105

- said control switches for transmitting said revertive impulses comprising a relay, the operation of which transmits impulses to said registering and controlling mechanism.
- 5 8. In a telephone exchange system, the combination of a plurality of switching stages, a plurality of conversation switches at each switching stage, a control switch common to a plurality of conversation switches, a registering and controlling mechanism, and means under control of said registering and controlling mechanism to control the operations of the control switch at two or more switching stages.
- 10 9. In a telephone exchange system, the combination of a plurality of conversation switches, a control switch connected in permanent multiple relation with said plurality of conversation switches, a relay individual to each conversation switch, and means for operating the relay of any conversation switch whereby said control switch is connected with a conversation switch by its operated relay.
- 15 10. In a telephone exchange system, the combination of a plurality of conversation switches, a control switch common to said conversation switches, a relay individual to each conversation switch, and means for operating the relay of any conversation switch whereby the control switch is operatively associated with said conversation switch.
- 20 11. In a telephone exchange system, the combination of a group of conversation switches, connected with groups of lines, a control switch, means for predeterminedly operating one of said conversation switches, means for associating said control switch with the predetermined conversation switch,
- 25 40 means for then advancing said control switch, registering and controlling mechanism, means controlled by said mechanism for controlling the advance of said control switch, and means controlled by said control switch when it advances to apply a marking potential to a wanted line or group of lines in said conversation switches, said control switch in its advance serving to send revertive impulses to said register mechanism.
- 30 50 12. In a telephone exchange system, the combination of a plurality of conversation switches, a control switch common to said conversation switches, means for advancing said control switch to a particular position in two selecting movements, a registering and controlling mechanism, a loop circuit extending from said control switch to said registering and controlling mechanism, and means controlled by said control switch in its selective movements to send revertive impulses to said registering and controlling mechanism by grounding one side of said loop circuit.
- 35 60 13. In a telephone exchange system, the combination of a plurality of conversation switches, a control switch common to said
- conversation switches, means for advancing said control switch to a particular position in two selecting movements, a registering and controlling mechanism, a loop circuit extending from said control switch to said registering and controlling mechanism, and means controlled by said control switch in its selective movements to send revertive impulses to said registering and controlling mechanism by grounding one side of said loop circuit, and means in said registering and controlling mechanism for opening said loop circuit to stop the movement of said control switch.
- 40 70 14. In a telephone exchange system, the combination of a plurality of conversation switches, a control switch common to said conversation switches, means for advancing said control switch to a particular position in two selecting movements, a registering and controlling mechanism, and means under control of said control switch for sending a set of reverting impulses to said registering and controlling mechanism during each of said selecting movements.
- 45 75 15. In a telephone exchange system, the combination of a plurality of conversation switches, a control circuit and an auxiliary switch, and means for causing said auxiliary switch to associate said control circuit with the conversation switch and also to control the advance of said conversation switch to a wanted position.
- 50 80 16. In a telephone exchange system, the combination of a plurality of conversation switches having sets of contacts, a common control circuit connected in multiple relation to said conversation switches, a switching device individual to each conversation switch for connecting its associated conversation switch with said common control circuit, an auxiliary switch associated with said common control circuit, and means for causing said auxiliary switch to first hunt for a contact set particular to a conversation switch and then causing the operation of the switching device individual to said conversation switch and then to subsequently advance to a further position to another set of contacts in the bank of said conversation switch.
- 55 100 17. In a telephone exchange system, the combination of a plurality of conversation switches having groups of outlets, a control circuit common to a plurality of said conversation switches, an auxiliary switch associated with said control circuit, and means for first causing said auxiliary switch to advance to certain positions to cause said control circuit to become associated with a conversation switch, and then advance a second time to control the advance of the conversation switch to a wanted group of outlets.
- 60 105 18. In a telephone exchange system, the combination of a plurality of conversation switches having groups of outlets, a control circuit common to a plurality of said conver-

sation switches, an auxiliary switch associated with said control circuit, means for first causing said auxiliary switch to advance to certain positions to cause said control circuit to become associated with a conversation switch, and then advance a second time to control the advance of the conversation switch to a wanted group of outlets and means for causing said auxiliary switch to advance a third time to control the advance of the conversation switch to a particular outlet in the wanted group.

19. In a telephone exchange system, the combination of a plurality of conversation switches having groups of outlets, an auxiliary switch provided with contacts, associated with said conversation switches, means for selecting one of said conversation switches for use and causing a certain potential to be connected to a contact of the auxiliary switch corresponding to the selected conversation switch, means for causing said auxiliary switch to advance to said contact, a register controller, means under control of said register controller to cause the auxiliary switch to advance to mark a wanted group of outlets in the conversation switch, and means to cause a second advance of said auxiliary switch, the advance of said switch causing revertive impulses to be sent to said register controller.

20. In a telephone exchange system, the combination of a group of conversation switches, a common control circuit comprising an associated auxiliary switching mechanism, means under control of said auxiliary switching mechanism for controlling the operation of any one of said conversation switches, registering and controlling mechanism for receiving impulses, and means in response to said impulses to control the operation of said auxiliary switching mechanism, and means whereby said control circuit is engaged for controlling the operation of the conversation switch after the registering and controlling mechanism is in condition to effect its control.

21. In a telephone exchange system, the combination of a plurality of switching stages, conversation switches at each of said stages, control switches common to said conversation switches at said stages, registering and controlling mechanism, means under control of said common control switches for sending revertive impulses to said registering and controlling mechanism, and means for delaying the engagement of the control switches at the switching stages until the registering and controlling mechanism is in readiness to receive the reverting impulses.

22. In a telephone exchange system, the combination of a plurality of switching stages, a plurality of conversation switches at each switching stage, control switches common to said conversation switches, register-

ing and controlling mechanism, means associated with said mechanism for receiving signals, and means for thereafter sending forward signals to the control switches at the various switching stages, and means controlled by said control switches for controlling said conversation switches.

23. In a telephone exchange system, the combination of a calling line and automatic switching mechanism, registering and controlling mechanism, a conductor, means under control of said registering and controlling mechanism for controlling the operation of said automatic switching mechanism over said conductor, a supervisory tone signal, and means for applying said supervisory tone signal to the calling line over a conductor over which the registering and controlling mechanism effects the control of the automatic switching mechanism.

24. In a telephone exchange system, the combination of a calling line, a link circuit having talking conductors and a transmission bridge, means for transmitting impulses from said calling line, registering and controlling mechanism for recording said transmitted impulses, an auxiliary switch for connecting said mechanism to said link circuit, and means for connecting a tone signal to the calling line over said conductors from the outgoing side of the transmission bridge when the registering and controlling mechanism is in condition to record the transmitted impulses.

25. In a telephone exchange system, the combination of a calling line, a conversation switch having access to a group of lines, means for causing said switch to repeatedly hunt for an idle line in said group, a registering and controlling mechanism for recording a wanted number, means for associating said mechanism with said conversation switch, and means for applying a tone signal to the calling line from said registering and controlling mechanism if said conversation switch does not find an idle line in the group within a predetermined time.

26. In a telephone exchange system, the combination of a final selector switch having access to single lines and to one or more groups of lines, means for first advancing the final selector switch to the first line of a group and for thereafter causing it to continue its advance to an idle line in said group or to the last line in the group without testing the condition of lines passed by it in its continued advance to the free or last line.

27. In a telephone exchange system, the combination of groups of selector switches for connecting with individual lines and free lines in any one of a plurality of groups of lines, a control switch, means for connecting said control switch with any one of said groups of selector switches, and means for causing said control switch to test the lines

of said groups of lines of the selector switch to which it is connected.

28. In a telephone exchange system, the combination of a group of conversation switches for selecting lines, a control switch provided with contacts, means for operatively associating said control switch with any one of the group of conversation switches, means for transmitting impulses to advance a conversation switch to a line determined by the transmitted impulses, and means for applying a discriminating potential to contacts of said control switch whereby a busy signal is sent to the calling line if the conversation switch is advanced to a busy line.

15 29. In a telephone exchange system, the combination of a group of final conversation switches for selecting free lines in one or more groups of lines, a control switch connected in permanent multiple relation to all the switches of said group, means for placing one of said switches in use, means for operatively associating said control switch with the conversation switch placed in use, and means for causing said control switch to control the advance of the conversation switch to a free or the last line of the group of lines.

30. In a telephone exchange system, the combination of a plurality of selector switches having access to groups of lines, a talking circuit, means for controlling said selector switches by impulses over said talking circuit, a control switch, means for operatively associating said control switch with any one of said selector switches, and means in response to said impulses for causing said control switch to mark an idle line in the group of lines of the selector switch with which it is associated.

40 31. In a telephone system the combination of a plurality of selector switches, a control circuit and an auxiliary switch common to said selector switches, means for associating one of said selector switches with said control circuit, means for causing said auxiliary switch to hunt for said selector switch and means for causing a further movement of said auxiliary switch to control the setting of said selector switch.

45 In witness whereof, we hereunto subscribe our names this 24th day of May, 1929.

50 GERALD DEAKIN.
LIPA POLINKOWSKY.
